ATTORNEY.

UNITED STATES PATENT OFFICE.

WILLIAM R. LEBERT, OF WATERTOWN, SOUTH DAKOTA.

FUNNEL.

1,411,284.

Specification of Letters Patent. Patented Apr. 4, 1922.

Application filed October 27, 1920. Serial No. 419,901.

To all whom it may concern:

Be it known that I, WILLIAM R. LEBERT, a citizen of the United States, residing at Watertown, in the county of Codington and State of South Dakota, have invented certain new and useful Improvements in Funnels, of which the following is a specification.

This invention relates to funnels and similar devices used for filling vessels with liquid and has for its primary object to provide an improved device of this character with automatically operated valve means by which the surplus liquid may be prevented from running out the discharge tube of the funnel after the latter has been withdrawn from a filled vessel.

An additional object is to provide manually operated means for enabling the user to open the valve of the funnel and permit the surplus liquid to be discharged into another vessel or container.

With these and other objects in view which will appear from the following disclosure, the invention resides in the details of construction, combination and arrangement of parts as will be hereinafter more fully described and pointed out in the accompanying drawings, wherein—

30. Figure 1 is a vertical sectional view disclosing the arrangement of the parts.

Figure 2 is a horizontal section taken through the upper portion of the funnel above the valve means and

35. Figure 3 a similar section taken through the discharge tube and between the guides therein.

In the drawings, the numeral 1 indicates a funnel of the usual or ordinary type having a wide-mouthed, usually conical vessel 2 terminating in the discharge tube 3 which is inserted in the mouth or neck of the bottle or other receptacle to be filled and in applying the present invention to such a funnel, 45 the mouth of the tube 3 is flanged or covered over with a disk 4 soldered or otherwise fastened rigidly in place. This disk has a center opening communicating with the interior of the tube to permit the contents of the vessel 2 to pass therein, and a valve disk 5 of greater diameter than the opening, is seated upon the disk 4 for normally closing the tube. Fastened to the valve 5 and depending below the seat is a short rod or wire stem 6 having an eye at its lower end so that it 55 may be loosely joined to one end of a lever 7, the latter being pivoted upon a stem 8.

Connected to the other end of this lever is a float member by means of which the valve 5 is unseated and this consists of a cork or other buoyant element 9 suspended within the tube 3 by means of a supporting wire or rod 10, the latter having an upper portion bent to provide a right angular extension 11 upturned at its end 12 and joined to the lever 7. The lever 7 and the extension 11 each project exteriorly of the tube through the side opening 13 and have their connected ends housed within the lower, enlarged pocket 14' of a protective casing or guard 14, arranged lengthwise of the funnel on the outside and of narrow width at its upper end to form a working channel or tube 14'' to accommodate a valve control rod 15. To facilitate the proper working of the parts, 75 guide strips 16 and 17 are positioned inside of the tube 3, above and below the lateral opening 13 and in relatively spaced relation. The guides consist of narrow strips of metal or other suitable material, supported transversely of the tube and providing each with an opening through which the rods 6 and 10 respectively pass. The opening in the lower guide, however, is elongated as indicated at 18 to 85 provide for slight lateral play of the rod 10 from one side of the tube to the other to effect the opening or closing of valve 5. To add some stability to the pendant wire 10 a balancing weight 19 is affixed thereto above 90 the cork 9 and any suitable fastening element such as a nut 20 may be screwed or otherwise secured to the wire beneath the cork for holding the latter in place.

Disposed within the upper channel portion of the casing 14 is a valve control rod 15 which is slidably supported the whole length of the channel by spaced apart bearing lugs 21; the lower end of the rod extending beyond the lowermost bearing and bent, 100 as at 22, to engage the pivoted lever 7 rearwardly of the pivot 8, as shown. At its upper end the rod projects exteriorly of the guard and is provided with a head piece 23 by which it may be readily depressed against 105 the tension of the coiled spring 24 the latter embracing the rod at its upper portion and normally tending to force the rod outwardly, one end of the spring engaging under the collar 25 of the rod and the other end being 110 supported on the lug 21.

Protecting the valve 5 is a conical hood 26 mounted upon the inside of the funnel 2 and adapted to project outwardly over the

valve as seen to advantage in Figure 1 of the drawings. This hood or shield is adapted to be hinged to the side of funnel as indicated at 27 so that it may be swung back 5 to uncover the valve 5 whenever desired. When in shielding position, the hood is supported by a stop or rest 28 formed of angle members secured to the funnel wall below the end 27 and projecting outwardly to engage and support the hood when it is thrown 10 forward above the valve 5. Being of smaller diameter than the base of the hood, the valve 5 is completely covered by the overhanging hood and the sloping sides of 15 the latter cause the liquid which is poured into the funnel to flow past the valve disk without impinging directly upon the valve disk.

In operation, the tube 3 of the funnel is 20 inserted in the mouth of a receptacle and the shield 26 thrown forward over the disk 5. The valve is then opened by depressing rod 15 which causes the lower bent end 32 to strike against the pivoted lever 7, rocking it so that the float lever moves downwardly within the tube 3 while the valve stem moves upwardly to unseat the disk 5 from the seat 4. Ordinarily, when filling a receptacle, the liquid is poured into the funnel in a steady stream and this stream would 30 usually fall with some force upon any valve means associated with the discharge tube. In the present instance however, the shock or brunt of the falling stream is sustained 35 by the shield 26, which projects over the valve and this saves the latter from injury, increasing the effectiveness and usefulness of the funnel. Being pointed and provided with sloping walls, the shield readily absorbs 40 the force of the impinging liquid which is easily broken up and withdrawn from the sloping sides of the funnel so that it drips free of the valve disk 5 which is elevated above the opening 4 through which 45 the flowing liquid passes. As the liquid rises in the receptacle and enters the tube, the float 9 rises with it, rocking the lever 7 on its pivot until the valve disk is seated, closing the openings 4 and shutting off further 50 discharge through the tube. The funnel may then be disjoined from the receptacle and the surplus liquid remaining within the conical vessel 2 of the funnel easily returned to its original container or 55 charged into some other receptacle. In any event, the discharge of such surplus liquid will be effected, merely by placing the thumb or finger against the head 23 of the rod 15 and depressing the latter until the 60 valve 4 has been opened. Should it at any time be necessary that the valve 5 be retained in open position against the closing action of the rising float, it may be accomplished by holding the rod 15 depressed so 65 that its bent end 2 is extended to provide

an abutment against which the outer end of the lever will contact and be held against further upward movement. Accordingly, the valve may then be closed slowly and in successive steps by the gradual relaxation of pressure on the rod 15, permitting the lever to turn slowly or gradually on its pivot. It will thus be seen that with these improvements, a funnel will be found more serviceable and economical, there being no waste 75 or loss of the liquid during the filling operation.

Although the foregoing may be said to comprehend the preferred embodiment of the invention, it is to be understood that minor changes in the construction, embodiment of parts, etc., may be resorted to as fall within the scope of the invention claimed.

What I claim as new and desire to secure 85 by Letters Patent is:—

1. A funnel having a valve-controlled discharge tube, a casing arranged on the outside of said funnel and communicating with the tube, and manually operated means in 90 said casing for opening the valve of the discharge tube.

2. A funnel having a valve stem at one end of the discharge tube, a float member at the other end, a pocket formed on the outside of said tube and pivotal means in 95 said pocket for mutually contracting and separating said stem and float member alternately for opening and closing the valve.

3. A funnel having a valve stem at one 100 end of the discharge tube, a float member at the other end, a pocket formed on the outside of said tube, pivotal means in said pocket and projecting into said tube for mutually contracting and separating the said 105 tube and float member alternately for opening and closing the valve, and a controlling rod depressible against said pivotal means for limiting movement of said pivotal means.

4. A funnel having its discharge tube provided with a side opening, a guard casing affixed to the outside of said funnel and communicating with the side opening, a valve for closing the discharge tube, a float below the valve, a pivoted connection between said 110 valve and float, said connection supported within said casing and working through the side opening in the tube, and a depressible rod, slidably supported within said casing, for abutment with said pivoted connection. 115

5. A funnel having a float valve arrangement for opening and closing the discharge tube and a conical shaped hood hinged to the funnel above said discharge tube, said hood covering the valve and adapted to protect it from the impingement of liquid poured into the funnel. 120

In testimony whereof I affix my signature.

WILLIAM R. LEBERT.
